UNITED STATES PATENT OFFICE.

ROCKWELL L. GALLUP AND WALTER G. WACHS, OF CHICAGO, ILLINOIS, ASSIGNEES TO BARRY-WEHMILLER MACHINERY COMPANY, OF ST. LOUIS, MISSOURI, A CORPORATION OF MISSOURI.

BOTTLE-WASHING MACHINE.

1,273,603.

Specification of Letters Patent. Patented July 23, 1918.

Application filed January 2, 1915. Serial No. 131.

To all whom it may concern:

Be it known that we, ROCKWELL L. GALLUP and WALTER G. WACHS, citizens of the United States, both residing at Chicago, in the county of Cook and State of Illinois, have jointly invented certain new and useful Improvements in Bottle-Washing Machines, of which the following is a specification.

10 This invention relates in general to bottle washing machines and more particularly to a machine for brushing the outside of bottles, especially after such bottles have been subjected to a prior soaking or other cleaning operation.

To thoroughly clean bottles for reuse so that they will be as bright and clear as when new it is necessary that the outside of the bottles be thoroughly scrubbed and brushed

20 from neck to base.

It is the object of our invention to provide a machine which will automatically and continuously remove bottles from a bottle carrier, thoroughly clean the outside of the bottles and deliver them to conveying mechanism which will carry them to a desired delivery point, for example the bottle filling machine.

Other objects and advantages of our invention will be apparent as it is better understood by reference to the following specification, taken in connection with the accompanying drawings in which—

Figure 1 is a front elevation of the machine;

Fig. 2 is a plan view thereof;

Fig. 3 is a vertical section on the line 3—3 of Fig. 2;

Fig. 4 is a detail partially in section of the mechanism for receiving and depositing bottles in the machine;

Fig. 5 is a similar view showing the bottle delivered to the machine and ready for further treatment;

45 Fig. 6 is a vertical section through a portion of the structure on the line 6—6 of Fig. 4;

Fig. 7 is a detail in section of the conveyer mechanism for removing bottles from the machine;

Fig. 8 is a detail in section of the mechanism for spinning the bottles during the brushing operation.

55 Fig. 9 is a detail of the means for centering the bottles on the spinning mechanism, and

Fig. 10 is a detail partially in section of a slightly modified form of bottle receiving mechanism.

Referring to the drawings, 1 indicates a suitable frame adapted to support the mechanism. The frame is provided at its center with an upwardly extending portion 2 of pyramidal or other suitable form. One end of a shaft 3 is mounted in a bearing 4 at the upper end of the extension 2. The shaft 3 is adapted to be driven from any suitable source of power. A sprocket 5 on the shaft 3 is connected by means of a chain 6 or other suitable driving mechanism with a sprocket 7 on a shaft 8. The shaft 8 is provided with a worm 9 which meshes with the worm gear 10 secured to the vertical cam shaft 11. The cam shaft 11 is journaled in suitable bearings 12 in the frame 1 and is provided with a plurality of cam tracks 36, 37, 38, 39 and 40 which coöperate with suitable mechanism, presently to be described, for operating the various parts of the mechanism as the shaft 11 is rotated.

Secured to the lower end of the cam shaft 11 is a mutilated gear 13 coöoperating with a mutilated gear 14 secured to a vertical shaft 15 suitably journaled in the frame 1. The gear 13 is provided with teeth on one half only of its circumference, the remaining portion of the circumference being finished to the pitch circle of the gear. The gear 14 is provided on each half of its circumference with a number of teeth equal to the number of teeth on the gear 13, but

between each set of teeth a space is allowed in which the blank portion of the gear 13 is adapted to slide during one half of a revolution thereof until the teeth thereon again engage the teeth of the gear 14. It will be understood that we have provided means whereby upon a half revolution of the shaft 11 and its gear 13 the gear 14 and the shaft 15 are rotated through one-half of a revolution, after which the gear 14 and the shaft 15 remain idle while the gear 13 completes its revolution. Upon reengagement of the teeth of the gear 13 with the teeth of the gear 14, the gear 14 is driven through another half revolution, which is followed by another idle period. We have thus provided for intermittent rotation of the shaft 15 from the constantly moving shaft 11.

Upon the upper end of the shaft 15 is a sprocket 16 and a similar sprocket 17 is mounted on a stub shaft 18 journaled in

suitable bearings at the other end of the machine. A chain conveyer 19, provided with a plurality of members 20 forming pockets each adapted to contain a single 5 bottle, is disposed about the sprockets 16 and 17 and adapted to be driven by the sprocket 16 in the direction indicated by the arrow in Fig. 2. The conveyer 19 is provided at intervals with anti-friction 10 supporting rollers 21 which run on suitable tracks 22 secured to the frame 1 of the machine. Rollers 21' are also provided to engage with tracks 22' between the sprocket wheels 16 and 17 to hold the chain conveyer 15 19 and the members 20 in proper lateral alignment. The pockets 20 comprise a back plate 23 and side plates 24 integral therewith or secured thereto, the back plates 23 being secured in any suitable manner to the 20 chain conveyer 19. Plates 25, of wood or other suitable material adapted to prevent breakage of the bottles, are secured to the back plates 23. Beneath the members 20 and extending nearly or wholly around the 25 machine is a suitable shelf 26 carried by the frame 1 and adapted to support the bottles as they are moved through the machine by the chain conveyer 19 and the members 20.

Referring to Fig. 3 of the drawings, 27 30 indicates a bottle carrier moving in suitable tracks 28 and carrying bottle holders 29. This carrier is of sufficient width to carry a plurality of bottles, for example 9, and may be the carrier of a bottle washing apparatus 35 disclosed in the copending application of Rockwell L. Gallup, Serial No. 647,005, filed August 31, 1911, or the carrier may be one which is fed by hand at any suitable distant point and adapted merely to deliver 40 bottles to the outside brushing machine.

Upon brackets 30 secured to the frame 1 a shield 31 is mounted, which is adapted to prevent the bottles from falling from the 45 holders 29. A shaft 32 is mounted in the brackets 30 and a plurality of bell-crank levers 33 having weighted ends 34 are loosely mounted on the shaft 32. The opposite ends of the bell-crank levers 33 are disposed to engage the bottoms of the bottles as they are 50 delivered to the machine and are provided with pads 35 of rubber or other suitable material.

The bottle-receiving mechanism consists of a shelf 41 comprising a pair of longitudinal members 42 and transverse members 43 secured thereto adapted to receive and center the bottles and to prevent sidewise movement thereof. The shelf 41 is pivotally mounted through links 44 on extensions 45 of the brackets 30. The brackets 30 are provided with slots 46 and the shelf 41 is provided at either end adjacent its inner side with rollers 47 pivotally secured thereto and adapted to move in the slots 46. Links 48 65 connect the inner side of the shelf 41 with

levers 49 secured to a shaft 50 journaled in the frame 1. A lever 49' is secured to the shaft 50 and provided with a roller 51 adapted to coöperate with the cam slot 38, whereby, as the shaft 11 is rotated, the link 70 48 will be reciprocated and will move the shelf 41 from the position indicated in Fig. 4 of the drawings to the position indicated in Fig. 5 of the drawings. The bottles on the shelf 41 are thereby disposed on the shelf 75 26 between the side walls 24 of the pockets 20 in position to be moved through the machine by the chain conveyer 19.

To free the bottles from the bottle carrier 27 I have provided means to positively 80 force the bottles from the holders 29 when the bottles are disposed in proper relation to the shelf 41. This means comprises a plurality of plungers 52 mounted in a suitable supporting means 53 and secured to a transversely extending rod 54. A pair of levers 55, secured to the shaft 55', operatively engage the rod 54 and levers 56, secured to the shaft 55', are connected by links 56' to the levers 57, the latter being secured 90 to a shaft 58 journaled in the frame 1. A lever 57' is secured to the shaft 58 and is provided with a roller 59 coöoperating with cam slot 36. It will be readily understood that as the shaft 11 is rotated the plungers 95 52 will be operated to force the bottles in the bottle holders 29 forwardly upon the shelf 41. The bell-crank levers 33 engage the bottoms of the bottles as they are forced from the bottle holders 29 and prevent overthrow 100 thereof. It is to be understood that the conveyer 29 is moved intermittently by means of any suitable mechanism and that the cam slots 36 and 38 are timed to operate the plungers 52 when the shelf 41 is in proper 105 position to receive bottles and when a row of bottle holders is disposed in front of the plungers 52 in position to deliver the bottles to the shelf 41.

As has been previously explained the 110 chain conveyer 19 is intermittently moved forwardly a distance equal to approximately one-half the circumference of the sprocket 16 at each complete revolution of the constantly moving shaft 11 and the sprocket 16 115 and the chain conveyer 19 remain idle during one-half of a revolution of the shaft 11 following each forward movement. The gears 13 and 14 are timed with respect to the cam tracks 36 and 38 so that when a row 120 of bottles is disposed by the conveyer 27 in position for delivery to the machine the plungers 52 will first be operated to force the bottles onto the shelf 41, the shelf 41 will be moved into the position shown in Fig. 5 to deposit the bottles in the pockets 20 and the chain conveyer 19 then will be moved forwardly to remove the bottles. The circumference of the sprocket 16 is such that a half revolution thereof will move the chain 125 130

conveyer 19 a distance sufficient to carry the row of bottles beyond the shelf 41 and to dispose a new set of empty pockets in position to receive the next row of bottles, as indicated in Fig. 2. The operation of this portion of the machine is then repeated. The bottles will be moved by the intermittent actuation of the conveyer 19 along the shelf 26 until they are disposed on the side 10 of the machine opposite the bottle receiving side where they are subjected to the brushing operation.

The mechanism for brushing the bottles will now be described. A plurality of 15 brushes 60 are secured to a shaft 61 rotatably mounted in the bearings 62 forming a part of the links 63. The links 63 are connected by levers 64 to a shaft 65 journaled in the frame 1 of the machine. A lever 66 20 is secured to the shaft 65 and is provided with a roller 67 adapted to engage with the cam track 37. A pair of brackets 68 are secured to the frame 1 and are provided with slots 69 forming tracks to guide the 25 rollers 70 secured to the shaft 61. The lower ends of the slots 69 turn outwardly, as shown in Fig. 3, so that the brushes in their lowermost positions are withdrawn from contact with the bottles. It will be 30 readily understood that as the shaft 11 revolves, the cam track 37, will through lever 66, shaft 65, levers 64 and links 63, move the shaft 61 and the brushes 60 inwardly, and upwardly in contact with the bottles. 35 In order to limit the upward movement of the brushes 60 when bottles of different sizes are treated we provide the pins 71, having threaded ends 72, adapted to be inserted in suitable openings 73 in the bracket 68, 40 whereby the pins 71 are disposed across the slots 69 in the path of the rollers 70 to limit the upward movement thereof. The link 63 comprises the telescoping sections 74 and 75, the latter being provided with pins 76 engaging 45 slots 77 in the former to limit the relative movement of the sections. A spring 78 is disposed between the end of the section 75 and an abutment within the section 74, and normally holds the sections in extended position. This provides for lost motion in the link 63 and it will be readily understood that when the pins 71 are in use to limit the upward movement of the brushes 60 the levers 64 will be allowed to make the 50 full reciprocatory movement provided for by the cam track 37 and the connecting means but the upward movement of the brushes 60 will stop at a position fixed by the pins 71. 60 The shaft 61 and the brushes 60 are constantly rotated by means of a belt 79 which is disposed about a pulley 80 secured to the shaft 61 and is driven in the direction indicated by the arrow in Fig. 3 by a pulley 81 65 on the stub shaft 82 journaled in the frame

1 and driven from any suitable source of power. In order to allow the vertical reciprocation of the shaft 61 the belt 79 is disposed about an idler 80' on the weighted lever 81' pivoted to the frame 1 and over 70 a pulley 82' secured to the shaft 83 journaled in the frame 1. It will be readily understood from the foregoing description that as the shaft 61 is reciprocated the pulley 80' on the weighted lever 81' will be raised and 75 lowered and will maintain the proper tension in the belt 79.

Journalized in the frame 1 in front of the brushes 60 are a plurality of spindles 84 each provided at its lower end with a bevel pinion 85 engaging with a corresponding bevel gear 86 on the shaft 83 which is constantly rotated, as previously described. The upper ends of the spindles 84 are flanged at 87 and provided with extensions 88. Circular tables 89 are mounted, in circular openings in the shelf 26, on the extensions 88 and frictionally engage the flanges 87. A brake, comprising a pin 90 mounted in a recess of the shelf 26 and forced forwardly 90 by a spring 91, engages with the periphery of each of the tables 89 and normally holds them from rotation with the spindles 84. Mounted above each of the tables 89 in suitable guides 92, in a bracket 93 secured to 95 the upwardly extending portions 2 of the frame 1, are a plurality of reciprocatory spindles 94 carrying weights 95 at their upper extremities. The spindles 94 pass through suitable openings in a longitudinally extending member 96, the downward movement of the spindles 94 being limited by collars 96' secured thereto and resting on the member 96. The member 96 is engaged at either end by the bifurcated ends 97 of 100 the levers 98 secured to a shaft 99 journaled in the upwardly extending portion 2 of the frame 1. A lever 101 is secured to the shaft 99 and is provided with a roller 102 engaging with the cam track 40. It will be 105 readily understood that as the shaft 11 rotates the cam track 40 will through the lever 101, shaft 99, levers 98 and the longitudinally extending member 96 raise and lower the spindles 94. 110

The lower ends of the spindles 94 are provided with pivots 103 adapted to enter the mouths of the bottles, the pivots being provided with cushions 104 of rubber or other suitable material to prevent breakage and 115 seal the bottles against the entrance of water during the brushing operation. The pivots 103 are provided with a reduced extension 105 and a flanged portion 106 having a ball race formed therein to receive the balls 107. 120 A pair of semi-cylindrical casings 108 engage the extension 105 beneath the flange 106 and are secured by a rivet 109 or other suitable means to an extension 110 of each spindle 94, a hardened plate 111 being pro- 125

vided above the balls 107 and the remaining space within the casings 108 being filled by a member 112, thus forming a rigid construction. Loosely mounted on each of the spindles 94 is a member 113 provided with a flanged lower portion 114 adapted to engage with and center the bottle neck so that the pivot 103 will enter the mouth thereof as the spindle 94 descends. Inasmuch as it is desirable to brush the bottle neck I have provided means for lifting the member 113 when the brushes 60 are moved upwardly comprising an extension 115 on each of the members 113 which is adapted to be engaged by a bar 116 slidably mounted in slots 117 in the brackets 68 and provided with rollers 117' adapted to engage with and travel on the extensions 63' of the links 63. As the upper ends of the links 63 move inwardly and upwardly the bar 116 travels in advance of the brushes 60 and raises the members 113 out of the path of the brushes leaving the necks of the bottles exposed for brushing.

25 To properly center the bottles upon the tables 89, a plurality of reciprocating members 118 slidably mounted in the frame 1 are provided at one end with arms 119 carrying rollers 120, of any suitable material, 30 adapted to engage with a bottle. The opposite ends of the members 118 are secured to a longitudinally extending member 121 disposed between the bifurcated ends 122 of the levers 123 secured to a shaft 124 35 journaled in the frame 1. A lever 125 is secured to the shaft 124 and is provided with a roller 126 adapted to engage the cam track 39. It will be readily understood that as the shaft 11 rotates the cam track 39 will, 40 through the lever 125, shaft 124, levers 123 and the longitudinally extending member 121 reciprocate the members 118 and cause the rollers 120 to center the bottles on the tables 89.

45 To remove the bottles from the machine after the brushing operation, a constantly moving belt conveyer 127 driven from any suitable source of power is disposed about a pulley 128 mounted on the stub shaft 129 50 journaled in a bracket 129' secured to the frame 1 of the machine. A supporting shelf 130 having side flanges 131 forming a trough is disposed beneath the belt conveyer 127. A plate 132 is secured to the shelf 26 overhanging the belt conveyer 127 and provides a smooth path for the bottles as they pass onto the belt conveyer. The belt conveyer 127 is moved at a speed slightly in excess of the speed of movement of the pockets 20 on the 60 chain conveyer 19 and as will be readily seen by reference to Fig. 2 the bottles will be picked up by the belt conveyer 127 and withdrawn from the pockets 20 as the chain conveyer 19 carrying the pockets passes 65 around the sprocket 17.

It is believed that the operation of the machine will be readily understood from the foregoing without further description of the structure thereof. At each period of rest of the carrier 27 a row of bottles will be disposed on the shelf 41. Simultaneously the plungers 52 will be actuated by the cam track 36 through the intermediate connections to push the bottles forwardly upon the shelf 41 which will then be moved to the position shown in Fig. 5 by means of the cam track 38 and the connecting mechanism to deposit the bottles on the shelf 26 in the pockets 20 of the chain conveyer 19. The teeth on the gear 13 will then engage the 80 teeth on the gear 14 and turn the shaft 15 and the sprocket 16 through a half revolution moving the chain conveyer and the bottles in the pockets 20 beyond the shelf 41 and disposing a set of empty pockets in position to receive a row of bottles.

Assuming that the machine is full of bottles, when the movement of the sprocket 16 ceases, a row of bottles will be disposed upon the tables 89 in front of the brushes 60. The cam track 39 will through the intermediate mechanism force the rollers 120 into engagement with the bottles and center them on the tables 89. The cam track 40 will then through the intermediate mechanism allow the weighted spindles 94 to descend until the pivots 103 enter the mouths of the bottles, the flanges 114 assisting in centering the necks of the bottles. The weight of the spindles 94 is sufficient 100 to provide for a frictional driving engagement between the tables 89, previously held by the brakes 90, and the flanges 87 of the constantly rotated spindles 84 and between the tables 89 and the bottoms of the bottles. 105 The bottles are thus rapidly spun on the pivots 103. Simultaneously the brushes 60 are moved inwardly and upwardly by the cam track 37, through the connecting mechanism, guided by the slots 69. As the 110 brushes move toward the necks of the bottles the members 113 are raised by the bar 116 so that the brushes contact with the entire neck. The brushes being constantly rotated, as previously described, the spinning bottles are subjected to a thorough brushing over their entire surface. Water is supplied to the bottles during the brushing operation by means of a perforated pipe 133 which is adapted to direct streams of water against the bottles. When the brushes 60 have completed their reciprocatory movement and have been withdrawn from the bottles by the outwardly extending portion of the slot 69 the spindles 94 are 115 raised and the rollers 120 withdrawn. The frictional driving force between the tables 89 and the flanges 87 is no longer sufficient to spin the bottles and the brakes 90 stop the rotation of the tables 89. The teeth on 120 125 130

the gear 13 are now in position to again engage the teeth of the gear 14 and the chain conveyer 19 is moved forward a distance equal to one-half the circumference of 5 the sprocket 16 or sufficient to remove the treated bottles from the tables 89, a new row of bottles being disposed over the tables. The treated bottles are moved by the chain conveyer 19 onto the belt conveyer 10 127 which removes them from the machine and carries them in an upright position to any desirable point, for example the filling machine. The operation of the machine is such that at each actuation of the chain 15 conveyer 19 a plurality of bottles, in this instance nine, are removed from the machine while a similar number of bottle is moved into brushing position and the shelf 26 in front of the receiving mechanism is 20 cleared to receive a new row of bottles during the brushing period in which the chain conveyer 19 is idle.

In Fig. 10 of the drawings we have shown a slightly different form of bottle-receiving mechanism adapted for use in connection with a bottle carrier such as carrier 25 27 of Fig. 3. In the use of this form of our invention the bottles are allowed to fall by gravity from the holders 29 upon an inclined shelf 134 secured to a lever 135 pivotally mounted at 136 on a bracket 137 secured to the frame 1 of the machine. As the bottles are delivered their bottom edges rest on the shelf 26, each bottle being disposed 30 in one of the pockets 20. A link 138 connects the end of lever 135 to suitable cam operating mechanism (not shown) which turns the lever 135 about its pivot at suitable intervals, moving the shelf 134 to 35 vertical position to right the bottles on the shelf 26.

It will be understood that although we have described our machine as fed from a suitable conveyer the bottles may be supplied 40 by hand to shelf 41 or shelf 134, either of which will deposit the bottles on the shelf 26 at intervals or the bottles may be placed directly on the shelf 26 in the pockets 20.

50 It is to be understood that various changes may be made in the form, proportions and arrangement of the parts without departing from the spirit and scope of the invention or sacrificing any of its material 55 advantages, the forms herein described being merely preferred embodiments thereof.

I claim:

1. In a machine of the character described, the combination of a rotatable means to 60 support a bottle upon its base in upright position, a constantly rotating means disposed in frictional engagement with said rotatable means, and means to engage the neck of the bottle and cause frictional driving engagement between the bottom of the 65

bottle and said rotatable means and between said rotatable means and said constantly rotating means, whereby the bottle is spun about its vertical axis.

2. In a machine of the character described, 70 the combination of a rotatable means to support a bottle upon its base in upright position, a constantly rotating member disposed in frictional engagement with said rotatable means, means adapted to engage 75 the neck of the bottle and cause frictional driving engagement between the bottom of the bottle and said rotatable means and between said rotatable means and said constantly rotating member, whereby the bottle 80 is spun about its vertical axis, a brush, and automatic means for moving said brush in contact with the bottle.

3. In a machine of the character described, 85 the combination of a rotatable means to support a bottle upon its base in upright position, means normally holding said rotatable means against rotation, a constantly rotating member disposed in frictional engagement with said rotatable means, and 90 means adapted to engage the neck of the bottle and cause frictional driving engagement between the bottom of the bottle and said rotatable means and between said rotatable means and said constantly rotating 95 member, whereby the bottle is spun about its vertical axis.

4. In a machine of the character described, 100 the combination of a rotatable means to support a bottle upon its base in upright position, means normally holding said supporting means against rotation, a constantly rotating member disposed in frictional engagement with said rotatable means, means adapted to engage the neck of the bottle 105 and cause frictional driving engagement between the bottom of the bottle and said rotatable means and between said rotatable means and said constantly rotating member, whereby the bottle is spun about its vertical axis, a brush, and automatic means for moving 110 said brush in contact with the bottle.

5. In a machine of the character described, 115 the combination of a rotatable table adapted to support a bottle upon its base in upright position, a constantly driven spindle having means thereon frictionally engaging said table, a brake normally holding said table against rotation, and means adapted to hold a bottle in frictional engagement with said 120 table and to cause frictional driving engagement between said table and said frictional driving means, whereby the bottle is spun about its vertical axis.

6. In a machine of the character described, 125 the combination of a rotatable table adapted to support a bottle upon its base in upright position, a constantly driven spindle having means thereon frictionally engaging said table, a brake normally holding said table 130

against rotation, means adapted to hold a bottle in frictional engagement with said table and to cause frictional driving engagement between said table and said frictional driving means, whereby the bottle is spun about its vertical axis, a brush, and automatic means for moving said brush in contact with the bottle.

7. In a machine of the character described, the combination of a rotatable means adapted to support a bottle upon its base in upright position, constantly rotating means disposed in frictional engagement with said rotatable means, weighted means, including a pivot adapted to enter the mouth of the bottle, for holding the bottle in frictional engagement with said rotatable means and for causing frictional driving engagement between said rotatable and constantly rotating means, a shaft disposed normally with respect to the vertical axis of the bottle, a brush thereon, means for rotating said shaft, and automatic means for moving said brush into and out of engagement with the bottle disposed on said rotatable means.

8. In a machine of the character described, the combination of a rotatable table adapted to support a bottle upon its base in upright position, a constantly rotating member disposed in frictional engagement with said table, weighted means, including a pivot adapted to enter the mouth of the bottle, for holding the bottle in frictional engagement with said table and adapted to cause frictional driving engagement between said table and constantly rotating member, a rotatable brush, and automatic means for moving said brush into and out of engagement with the bottle disposed on said table.

9. In a machine of the character described, the combination of a rotatable table adapted to support a bottle upon its base in upright position, a constantly rotating member disposed in frictional engagement with said table, weighted means, including a pivot adapted to enter the mouth of the bottle, for holding the bottle in frictional engagement with said table and adapted to cause frictional driving engagement between said table and said constantly rotating member, automatic means for moving said weighted means into and out of engagement with the bottle disposed on said table, a brush, and automatic means for moving said brush into and out of engagement with said bottle.

10. In a machine of the character described, the combination of a shelf, a bottle conveyer, means for intermittently actuating said conveyer, means for receiving and depositing a plurality of bottles simultaneously in said conveyer in upright position with their bottoms resting on said shelf,

rotatable means disposed in the path of the bottoms of the bottles on said shelf to frictionally engage with the bottoms of the bottles and spin them about their vertical axes while the conveyer is at rest, a plurality of brushes, and automatic means for moving said brushes into engagement with the exteriors of the bottles during the spinning operation.

11. In a machine of the character described, the combination of a shelf, a bottle conveyer, means for intermittently actuating said conveyer, means for receiving and depositing a plurality of bottles simultaneously in said conveyer in upright position with their bottoms resting on said shelf, rotatable means disposed in the path of the bottoms of the bottles on said shelf to frictionally engage with the bottoms of the bottles and spin them about their vertical axes while the conveyer is at rest, a plurality of brushes, means for spraying the outside of the bottles, and automatic means for moving said brushes into engagement with the exteriors of the bottles during the spinning operation.

12. In a machine of the character described, the combination of a vertically disposed shaft adapted to be continuously rotated, an endless conveyer between the runs of which said shaft is located, said conveyer being adapted to receive a plurality of bottles in upright position, connecting means between said shaft and said conveyer, whereby the latter is intermittently actuated by the former, means for depositing bottles in said conveyer, means for brushing the bottles, a plurality of cam tracks on said shaft and means cooperating therewith for controlling said depositing and brushing means.

13. In a machine of the character described, the combination of a vertically disposed shaft adapted to be continuously rotated, a conveyer adapted to receive a plurality of bottles in upright position, connecting means between said shaft and said conveyer, whereby the latter is intermittently actuated by the former, means for depositing bottles in said conveyer, means for brushing the bottles, a plurality of cam tracks on said shaft, and connecting means between said cam tracks and said depositing and brushing means, whereby said depositing and brushing means are intermittently actuated.

14. In a machine of the character described, the combination of a plurality of rotatable tables, a constantly rotating member disposed in frictional engagement with each of said tables, means for intermittently and automatically disposing a bottle on each of said tables in upright position, a shaft, brushes thereon, and automatic means for

moving said brushes into engagement with the exteriors of the bottles and upwardly in engagement therewith and for returning said brushes to normal position.

- 5 15. In a machine of the character described, the combination of a plurality of rotatable tables, a constantly rotating member disposed in frictional engagement with each of said tables, means for intermittently 10 and automatically disposing a bottle on each of said tables in upright position, a shaft, brushes thereon, automatic means for moving said brushes into engagement with the exteriors of the bottles and upwardly in engagement therewith and for returning said brushes to normal position, and means to adjustably limit the upward travel of the brushes.
- 10 16. In a machine of the character described, the combination of rotatable tables, a constantly rotating member disposed in frictional engagement with each of said tables, means for intermittently and automatically disposing a bottle on each of said 15 tables in upright position, a plurality of brushes rotatably mounted contiguous to said tables, means for rotating said brushes, and automatic means for moving said brushes into engagement with the exteriors 20 of the bottles disposed on said tables and upwardly in engagement therewith and for returning said brushes to normal position.

- 15 17. In a machine of the character described, the combination of a plurality of rotatable tables, a conveyer adapted to intermittently dispose a bottle on each of said tables, a constantly rotating member disposed in frictional engagement with each of said tables, means disposed above each of 25 said tables and adapted when lowered to enter the mouths of the bottles and to act as pivots therefor, brushes contiguous to said tables, means for moving said brushes into engagement with the exteriors of the bottles 30 disposed on said tables and upwardly in engagement therewith, a vertically disposed shaft, and means connected therewith for controlling the actuation of said conveyer and brushes and the movements of said 35 pivot means.

- 40 18. In a machine of the character described, the combination of a rotatable means to support a bottle, a constantly rotating member disposed in frictional engagement 45 with each of said rotatable means, means for automatically depositing a bottle on said rotatable means upon its base in upright position, means for intermittently rotating said rotatable means, a brush, and automatic 50 means for moving said brush into contact with the exterior of the bottle disposed on said rotatable means.

- 45 19. In a machine of the character de-

scribed, the combination of a rotatable means to support a bottle upon its base in 65 upright position, a constantly rotating member disposed in frictional engagement with said rotatable means, a brush, and automatic means for moving said brush into contact with the exterior of the bottle disposed on 70 said rotatable means.

20. In a machine of the character described, the combination of a bottle conveyer, means for intermittently actuating said conveyer, rotatable means disposed in 75 the path of the bottoms of the bottles in said conveyer to engage with the bottoms thereof and spin the bottles about their vertical axes while the conveyer is at rest, a plurality of brushes, and automatic means for 80 moving said brushes into engagement with the exteriors of the bottles during the spinning operation.

21. In a machine of the character described, the combination of a bottle conveyer, rotatable means disposed in the path 85 of the bottoms of the bottles in said conveyer to frictionally engage with the bottoms of the bottles and spin them about their vertical axes while the conveyer is at 90 rest, a plurality of brushes, means for spraying the outside of the bottles, and automatic means for moving said brushes into engagement with the exteriors of the bottles during the spinning operation.

95 22. In a machine of the character described, the combination of a bottle conveyer, means for intermittently actuating said conveyer, rotatable means disposed in the path of the bottoms of the bottles in said 100 conveyer to engage with the bottoms of the bottles and spin them about their vertical axes while the conveyer is at rest, a plurality of brushes, automatic means for moving said brushes into engagement with the exteriors 105 of the bottles during the spinning operation, and means for removing the bottles from said conveyer.

110 23. In a machine of the character described, the combination of a plurality of rotatable tables adapted to support bottles in upright position, a plurality of spindles adapted to be moved into engagement with the necks of the bottles, means on said spindles adapted to engage with and center the 115 necks of the bottles, brushes, means for moving said brushes into engagement with the bottles, and means adapted to move in advance of said brushes to remove said centering means from the path of said brushes.
